INHALER

Abram Leenhousts and A. Donald Leenhousts,
Holland, Mich.

Application December 21, 1936, Serial No. 116,928

1 Claim. (Cl. 128—200)

This invention relates to inhalers, and is particularly concerned with the production of a novel and effective inhaler by means of which vaporized medicants may be inhaled into the throat or nostrils for the treatment of nasal or throat irritations, afflictions or the like, or for the absorption of ingredients into the body through such inhaling to have a beneficial effect for other purposes than merely the throat or nasal irritation or ailments.

It is a primary object of the present invention to produce an inhaler by which vapors from a liquid composition of the ingredients may be inhaled, wherein the liquid composition may be resupplied when depleted or exhausted, in which the inhaler is of a very compact form so that it may be readily carried in the pocket, and to provide the device with numerous features of novelty and of operation for sealing the same against escape of the liquid when not in use, but which is readily operated to position so that it may be used for the purposes for which it is designed. These and many other objects and purposes will be apparent upon an understanding of the invention had from the following description, taken in connection with the accompanying drawing, in which,

Fig. 1 is a perspective view of the completely assembled inhaler.

30 Fig. 2 is a central longitudinal vertical section therethrough.

Fig. 3 is a fragmentary sectional view of the upper end of the device with the cover removed.

Fig. 4 is an elevation of the upper part of the device shown in Fig. 3, and

40 Figs. 5, 6, 7 and 8 are horizontal sections taken substantially on the planes of lines 5—5, 6—6, 7—7 and 8—8, respectively, of Fig. 2, all sections being taken looking downwardly as indicated by the arrows.

Like reference characters refer to like parts in the different figures of the drawing.

In the structure disclosed by the drawing and showing one embodiment of our invention, an 45 outer tube 1 of thin sheet metal is provided, open at its lower end and interiorly threaded at such end and having a short inturned continuous annular flange 2 at its upper end. In a side of the tube a relatively long vertical slot 3 is cut.

50 In the upper end of the tube a plug 4 is mounted, being inserted at the lower end of the tube and pushed upwardly therein until the larger lower portion of the same comes against the flange 2 and with a short part of smaller 55 diameter extending through the openings which

is surrounded by said flange 2. A vertical pin 5 has its lower end with a head thereon embedded in the plug 4 which is of rubber or similar yielding material, the pin 5 extending upwardly above the plug 4. Two openings are made through the 5 plug 4 and into said openings, at the lower side of the plug, a long tube 6 and a short tube 7 are inserted at their upper ends, the tubes 6 and 7 preferably being of glass.

Above the plug 4 a disk 8 of metal is located 10 having a central opening to pass over the pin 5 about which it may turn. The disk 8 has an opening 9 therein extending vertically through the disk and at its under side has a lateral passage 10 extending to its edge, the opening and 15 the passing being so located that when the disk is turned to one position, as shown in Figs. 2 and 3, said opening 9 is directly above the tube 7 and the opening in the plug 4 in which the tube is inserted, and the lateral passage 10 communicates 20 with the opening into which the tube 6 is inserted. A short sleeve 11 of rubber is placed around the pin 5 above the disk 8, a washer 12 of thin metal placed over the upper end of the sleeve 11 and a pin 13 is inserted transversely 25 through a suitable opening made in the upper end of the pin 5, the sleeve 11 being compressed when this operation is performed whereby the disk 8 bears snugly against the upper side of the 30 plug 4.

A dome or cap 14 of sheet metal, open at its under side, is placed over sleeve 11 and the parts associated therewith above the disk 8, and at its lower end is spun into a bead 15 the terminal edges of which pass underneath an annular 35 flange made at the upper part of the disk 8, thereby making a permanent connection of the cap to the disk. In the uppermost part of the cap 14 an outlet opening 16 is pierced.

After the parts consisting of the tube 1, plug 40 4, tubes 6 and 7, disk 8, sleeve 11, washer 12, pin 13 and cap 14 have been thus assembled and secured together, a glass receptacle having vertical walls 17 and a closed lower end 18 is inserted into the tube 1, its upper end edges coming 45 against the lower side of the plug 4. A rubber cushion plug 19 is then inserted into the lower end of the tube 1 to bear against the bottom 18 and a screw plug 20 is threaded into the lower end of the tube 1 compressing the rubber plug 50 19 and pressing the upper end edges of the receptacle 17 against the rubber plug 4 thereby making a tight sealing connection. The receptacle 17 is of glass, preferably, and at a point substantially midway between its upper and lower 55

ends has a colored band 21 secured therearound, a part of which is visible through the slot 3. This band is for two purposes. It marks the level to which the receptacle 17 should be filled 5 with the medicinal liquid preparation shown at 22, and different colored bands may be used to indicate different medicinal compositions.

A covering shell of thin sheet metal is provided comprising, a section 23 closed at its upper end 10 and then outwardly flared and continued in a downwardly extending skirt 24. This covering member is adapted to be placed over the dome or cap 14 with the skirt 24 extending a distance downward over the upper end of the tube 1. In 15 one side of the skirt 24 an outwardly pressed vertical bead 25 is made and a horizontal slot 26 extends from and through said bead laterally for a distance as best shown in Fig. 1. Adjacent the upper end of the tube 1 a projection 27 is pressed 20 outwardly at a position where it may be located in said slot when the covering member is in place. The groove at the inner side of the rib 25 will pass said projection, so that on turning the cover plate to the right (Fig. 1) until the projection 25 comes to the groove 25, the cover may then be lifted vertically to remove the same.

At a point in the periphery of the bead portion 15 of the cap or dome 14 a second projection 28 is provided over which the bead 25 in the skirt 24 30 is passed in attaching or removing the cover member. When the cover member is attached or removed the two projections 27 and 28 must be in vertical alinement, as in Fig. 4. When in such vertical alinement the lateral passage 10 is in conjunction with the opening in the plug 4 in which the upper end of the tube 6 is inserted, and the opening 9 in disk 8 is in alinement with the short tube 7.

Therefore, whenever the cover member is applied or is removed the parts occupy such position, thereby providing a continuous passage from the outside through the lateral passage 10, through the tube 6 to the medicinal solution at 22 thence outwardly through tube 7 and the opening 9 and finally the opening 16 in the cap 14. When the cover has been applied in place and is turned so that the parts occupy the position shown in Fig. 1, the engagement of the cover with the projection 28 causes the disk 8 to turn with the 45 cover and move the disk so that the passage 10 and the opening 9 are moved out of operative conjunction with the tubes 6 and 7.

In using the inhaler described the cap 14 may

be applied to the nostril, for example, with the opening 16 in direct conjunction with the nostril, and then by inhaling through such nostril air will be drawn from the inhaler and other air to supply that withdrawn will be carried inwardly 5 through the tube 6 and bubble upwardly through the solution 22, which being of a vaporizable character, the air will carry with it various ingredients. Of course, the inhaler may be also used to draw the vapor charged air into the throat. After 10 the treatment has ended the cover is put in place and turned so as to position the projection 27 at the end of the slot as shown in Fig. 1 thereby completely closing the upper ends of the tubes 6 and 7.

The construction is one which is readily produced, easily assembled and is very practical and efficient for the purposes for which it is designed. To refill the receptacle 17 it is necessary only to unscrew the plug 20, remove the rubber member 20 19 and said receptacle, fill the receptacle to the required level and then replace the parts which have been removed all of which can be accomplished quickly and easily.

The invention is defined in the appended claims 25 and is to be considered comprehensive of all forms of structure coming within their scope.

I claim:

An inhaler comprising, an outer tube having an open lower end interiorly threaded, an in-turned continuous flange at the upper end of said tube, a plug having an annular shoulder thereon located in the upper end of said tube, said shoulder adapted to lie against the under side of said flange, a disc having an annular flange thereon disposed above and in contact with said plug, openings in said plug and disc adapted to coincide with each other, a radially extending passage in said disc connecting one of said openings with the outside air, an inner cap having an opening in the top thereof and an annular bead around the bottom thereof adapted to clip over the flange on said disc, a receptacle adapted to contain a liquid therein and be inserted within said outer tube, a short tube inserted in one of the openings in said plug, a long tube inserted in the other of said openings, and an outer cap adapted to fit over said inner cap and removable therefrom only when the respective openings in the disc and plug are in alinement with each other.

ABRAM LEENHOUTS.
